UNITED STATES PATENT OFFICE.

VERE B. EDWARDS, OF CORAOPOLIS, PENNSYLVANIA, ASSIGNOR TO DRAVO CONTRACTING COMPANY, OF PITTSBURGH, PENNSYLVANIA, A CORPORATION OF PENNSYLVANIA.

DRIVING GEAR FOR BOATS.

Application filed August 4, 1923. Serial No. 655,697.

To all whom it may concern:

Be it known that I, VERE B. EDWARDS, a citizen of the United States, residing at Coraopolis, county of Allegheny, and State 5 of Pennsylvania, have invented a new and useful Improvement in Driving Gears for Boats, of which the following is a full, clear, and exact description.

This invention relates to an improvement 10 in driving mechanism for boats, and more particularly to driving mechanism for driving paddle wheels located at the stern of towboats.

In some forms of boats of this character, 15 the paddle wheels are driven by connecting rods, located one at each end of the wheel, these rods being connected at one end either to crank pins on the wheel or cranks on the wheel shaft and at the other 20 end to crank pins or cranks connected to a transverse driving shaft on the stern of the boat, but forward of the wheel. This driving shaft is in turn driven by a suitable motor.

25 In other forms the paddle wheel is driven from a transverse driving shaft by two sprocket chains, one at each end of the paddle wheel, cooperating with sprocket wheels on the end portions of the driving shaft.

30 In both of the above mentioned forms of driving connections, considerable space is taken up at both sides of the deck at the stern of the boat; also, in the first case, the wheel is subjected to twisting stresses caused 35 by the shock when the speed of the wheel increases, due to the crank pins on the wheel passing through the plane of zero power application.

In the second mentioned form of drive 40 the chains not only take up space on both sides of the deck, but frequently one of the chains will stretch to a greater extent than the other, so that the major portion of the power, and very frequently the entire power 45 for driving the wheel, is applied at one side or end thereof. This variation in the length of the chains will also throw all of the power on one end of the driving shaft, so that both the paddle wheel and the driving shaft will be subjected to excessive 50 twisting stresses due to the unbalanced drive.

One of the objects of my invention is to 55 provide an efficient drive whereby I am enabled to economize in deck space utilized

by the wheel driving mechanism at the stern of the boat, reduce the twisting stresses to which the paddle wheel is subjected, and at the same time provide means whereby all of the driving mechanism for the paddle 60 wheel extends along substantially the longitudinal center of the boat.

The precise nature of my invention will be best understood by reference to the accompanying drawings, which will now be 65 described, it being premised, however, that various changes may be made in the details of constructions of the driving mechanism, without departing from the spirit or scope 70 of my invention as defined in the appended claims.

Figure 1 of the drawings is a sectional plan view of the stern of a boat of the barge type, having a paddle wheel extending across very nearly the full width of the 75 boat, together with driving mechanism constructed in accordance with my invention.

Figure 2 is a sectional view along the line II-II of Figure 1;

Figure 3 is a plan view of a modified 80 form of paddle wheel driving mechanism; and

Figure 4 is a detail sectional view of a portion of the paddle wheel shown in Figure 3. 85

In the drawings:

The reference character 2 designates the hull of a boat of the barge type, having substantially parallel sides and a truncated stern which is substantially the full width 90 of the beam. The hulls of boats of this character are usually very shallow, the engines or motors being usually near the bow or forward end of the boat, and the driving or paddle wheel at the stern of the boat, 95 considerable of the intermediate deck portion of the boat being utilized as cabin space for the officers and crew.

In boats of this kind the main driving shaft 3 usually extends from the motors or engines rearwardly under the deck or state-rooms to the stern of the boat. In the form shown, the rear end of the shaft 3 is rotatably mounted in a bearing 4 and carries a pinion 5. Rotatably mounted in 105 bearings 6 connected to suitable framing and above the level of the deck is a longitudinal shaft 7. This shaft, as well as shaft 3, extends longitudinally at approximately 110 the center of the boat.

As illustrated in Figures 1 and 2, two paddle wheel sections 8 may be connected to a shaft 9, journalled in bearings 10 on a frame work 11 extending rearwardly 5 from the hull of the boat.

Rotatably mounted in suitable bearings 12 on frame work supported from the deck of the boat is a short transverse shaft 13. Connected to the jack-shaft 13 is a bevel 10 gear 14 meshing with a similar gear 15 secured to the end of the shaft 7. Carried by the shafts 9 and 13 is a combined gear supporting frame 16 and gear casing provided with bearings for a short shaft 17 and its 15 gear 18. The gear 18 meshes, at one side, with a gear 19 on the shaft 13 and on the opposite side with a gear 20 on the shaft 9 of the paddle wheel. The three gears 18, 19 and 20 are enclosed by means of the gear 20 casing 16, while the bevel gears 14 and 15 are enclosed by a casing 21. A separate casing 22 may be provided for enclosing a gear 23 on the shaft 7, meshing with pinion 5 of the main driving shaft 3.

25 The gear frame 16 is of the floating type and is entirely supported by the shafts 9 and 13, so that if either side of the frame work is bent by the bumping of the boat and thereby shift the bearings 10 and shaft 9 out of their normal positions or alignment relative to the boat, the frame work 16 will be shifted with the shaft 9 and thereby avoid any binding of the gearing.

In the form shown in Figures 3 and 4, I 35 have designated parts corresponding to parts already described by the same reference character showing the letter "a" affixed thereto. In this embodiment, the paddle wheel driving gear 20^a is substantially the same diameter as the outer edge 40 of the paddle. This gear is preferably made up of segments secured within a channel 25 supported by means of a spider 26 extending radially from the hub of the paddle 45 wheel.

The shaft 13^a is operatively driven from shaft 7^a by means of bevel gears 14^a and 15^a. Obviously, the reduction between the gears 50 for driving the paddle wheel and the gear on the shaft 7^a need not be so great as in the form first described, as the diameter of the gear 20^a is very much greater than the diameter of the corresponding gear 20.

The advantages of my invention result 55 from the provision of driving mechanism for the paddle wheel at the stern of a boat in which substantially all of the driving mechanism is placed in a plane extending through the longitudinal center of the boat. 60 This enables a paddle wheel of greater effective width to be used.

A further advantage results from the provision of a gear supporting frame for the gearing between one of the driving shafts

and the paddle wheel shaft, which is float- 65 ingly supported by said shafts.

Further advantages arise from the reduction in straining stresses on the driving mechanism, the paddle wheel and on the frame for supporting the driving mecha- 70 nism.

Still further advantages arise from the increased deck space available for use by reason of the concentration of the driving mechanism.

I claim:

1. In a tow boat having rearwardly extending frame members on opposite sides thereof, a paddle wheel shaft journalled in bearings on the frame members and extending transversely of the boat, a transverse jack-shaft, a longitudinally extending power shaft, gearing connecting the jack-shaft to the power shaft, a gear frame floatingly supported by the jack-shaft and the paddle wheel shaft, and gearing connecting the jack-shaft to the paddle wheel shaft, some of which is carried by the floating frame, substantially as described.

2. In a tow boat having rearwardly extending frame members on opposite sides thereof, a paddle wheel shaft journalled in bearings on the frame members and extending transversely of the boat, a transverse jack-shaft, a longitudinally extending power 95 shaft, gearing connecting the jack-shaft to the power shaft, a gear frame floatingly supported by the jack-shaft and the paddle wheel shaft, gearing connecting the jack-shaft to the paddle wheel shaft, some of which is carried by the floating frame, and a gear casing connected to the floating frame covering the gearing between the jack-shaft and the paddle wheel shaft, substantially as described.

3. A tow boat of the barge type having a two-part stern paddle wheel, a shaft for the paddle wheel extending transversely of the boat, bearing supporting frame members for the shaft extending rearwardly 110 from the hull of the boat and at the sides thereof, a power shaft extending longitudinally of the boat, a transverse jack-shaft at the stern of the boat, gearing connecting the jack-shaft to the power shaft, a gear wheel 115 connected to the paddle wheel shaft between the two parts of the paddle wheel, a gear on the jack-shaft in alignment with the gear on the paddle wheel shaft, a floating gear frame supported on the jack-shaft and the 120 paddle wheel shaft, and an intermediate gear journalled on the floating frame meshing with the gear on the jack-shaft and the gear on the paddle wheel shaft, substantially as described.

In testimony whereof I have hereunto set my hand.

VERE B. EDWARDS.
